UNITED STATES PATENT OFFICE.

WALTER O. SNELLING AND GUY A. RUPP, OF ALLENTOWN, PENNSYLVANIA, AS
SIGNORS TO TROJAN POWDER COMPANY, OF NEW YORK, N. Y., A CORPORATION OF
NEW YORK.

EXPLOSIVE COMPOSITION.

No Drawing.

Application filed July 17, 1926. Serial No. 123,255.

Our invention relates to improvements in explosive compositions, and particularly in explosive compositions containing ferrosilicon.

- 5   The use of ferrosilicon as an ingredient of explosive compositions was known prior to our invention, and explosives containing comparatively large percentages of ferrosilicon were commercially made for a time, 10 but their manufacture has since been discontinued, as these explosives were found to possess too low efficiency to meet existing competitive conditions in the explosives industry.
- 15   We have found that the use of comparatively large percentages of ferrosilicon, particularly in low grade explosives, is undesirable, and that proper efficiency of explosive action is not obtained. We have discovered 20 further that the efficiency of ferrosilicon as an element of explosive mixtures drops off rapidly as increasing quantities are used, and that a very small amount of ferrosilicon forms a highly efficient and very desirable 25 constituent of an explosive composition, whereas this substance when used in larger amounts forms an undesirable constituent. This is probably due to the great affinity of ferrosilicon for oxygen, which causes it, 30 when present in large quantities, to rob the other combustible constituents in the explosive of the oxygen necessary for their combustion, producing iron oxide and silicon dioxide in the products of combustion of the 35 explosive instead of the gas-forming carbon monoxide and carbon dioxide that would otherwise be produced. As explosives owe their usefulness and their efficiency to the sudden production of a large volume of gas 40 at the instant of detonation, it will be evident that any constituent that modifies the explosive reaction by absorbing available oxygen with the production of a solid, non-volatile product will ordinarily reduce the 45 efficiency of the explosive of which such material is a constituent, but we have found that within certain small percentage limits, the amount of heat evolved in the oxidation 50 of ferrosilicon enables this material to be used to advantage, although when used in any quantity beyond the efficient limits which we have discovered, the use of the material leads to a reduction in gas volume

and to a marked falling off in the efficiency of the explosive.

We have further discovered that the use of small percentages, say from 1 to 4% of ferrosilicon, is of particular advantage in connection with explosives containing nitrostarch, and more particularly in explosives 60 whose sensitiveness is so low that they will not normally fire from the action of the detonator, although they fire with high efficiency from the action of a booster charge.

As an example of an explosive made in 65 accordance with the present invention, we may take 63.49 parts of sodium nitrate and 10 parts of ammonium nitrate, and coat these two salts jointly with 8.16 parts of trinitrotoluene, thus obtaining 81.65 parts of a mixture of 90/10 amatol and sodatol. The coating operation may be performed by heating the two salts to a temperature of approximately 100° C., adding the trinitrotoluene, 70 stirring until the molten trinitrotoluene has 75 thoroughly coated the two salts, and then cooling the resulting mixture.

To the 81.65 parts of 90/10 amatol and sodatol made as described above, we add .15 parts of mineral oil, .20 parts of sodium 80 bicarbonate, 3 parts of fetrosilicon, 6 parts of cornmeal, and 9 parts of nitrostarch. The resulting mixture is an explosive of great strength, but relatively insensitive, and to secure detonation the use of a strong 85 priming charge is desirable.

The invention, however, is not limited to explosives of low sensitiveness, and as an example of an explosive which is of higher sensitiveness and which makes use of the 90 same principle of employing a relatively small amount of ferrosilicon, we may take 51.93 parts of ammonium nitrate and coat it with 3.32 parts of trinitrotoluene, thereby obtaining 55.25 parts of 94/6 amatol. The 95 amatol is mixed with .25 parts of a mineral lubricating oil, .20 parts of zinc oxide, 3.30 parts of cornmeal, 2 parts of fetrosilicon, 25 parts of sodium nitrate, and 14 parts of nitrostarch. This provides an explosive of 100 great strength and good sensitiveness.

The general composition of an explosive made in accordance with this invention may vary in large degree, the essential feature of the invention residing in the use of an 105 amount of ferrosilicon only sufficient to give

the desired additional heat to the products of explosion, but insufficient in amount to materially reduce the gas volume of the resulting explosive by the absorption of available oxygen in the formation of the non-volatile oxides of iron and silicon. We have obtained the best results with quantities of ferrosilicon smaller than 5%, and in general prefer to use from 1% to 4% of this ingredient.

Our explosive also as stated above preferably contains nitrostarch, and the amount thereof in general may vary from 5% to about 20%. The remainder of the explosive composition may be ammonium nitrate, sodium nitrate or their equivalents, amatol and sodatol, together with carbonaceous material, such as cornmeal, wood pulp, ground vegetable ivory or like material, and such other ingredients of common usage as may be found desirable.

We claim:

1. An explosive composition comprising

nitrostarch and ferrosilicon, said ferrosilicon being present in amounts up to 5%. 25

2. An explosive composition containing from 1% to 4% of ferrosilicon and from 5% to 20% of nitrostarch.

3. An explosive composition of low sensitivity comprising nitrostarch and ferrosilicon, said ferrosilicon being present in amounts up to 5%. 30

4. An explosive comprising nitrostarch, ferrosilicon, ammonium nitrate and carbonaceous material, said ferrosilicon being present in amounts up to 5%. 35

5. An explosive composition comprising nitrostarch and ferrosilicon, the amount of nitrostarch being at least four times the amount of the ferrosilicon, and the combined amounts of ferrosilicon and nitrostarch being less than one-fourth of the total quantity of the explosive mixture. 40
